CLAIM

The ornamental design for an autoinjector with removable cap, as shown and described.

DESCRIPTION

FIG. 1 is a perspective view showing a new design for an autoinjector with removable cap with the removable cap disposed on the autoinjector;

FIG. 2 is a top view of the autoinjector with removable cap of FIG. 1;

FIG. 3 is a bottom view of the autoinjector with removable cap of FIG. 1;

FIG. 4 is a front view of the autoinjector with removable cap of FIG. 1;

FIG. 5 is a right-side view of the autoinjector with removable cap of FIG. 1;

FIG. 6 is a rear view of the autoinjector with removable cap of FIG. 1;

FIG. 7 is a left-side view of the autoinjector with removable cap of FIG. 1; and,

FIG. 8 is a perspective view showing the autoinjector with removable cap of FIGS. 1-8 with the removable cap removed from the autoinjector.

(Continued)

The dashed lines showing portions of the autoinjector with removable cap are included for the purpose of illustrating environment and form no part of the claimed design.

1 Claim, 5 Drawing Sheets
